PENDANT

Marindo De Stefano, Brooklyn, N. Y.

Application December 12, 1952, Serial No. 22,681

Term of patent 14 years

(Cl. D45—17)

To all whom it may concern:

Be it known that I, Marindo De Stefano, a citizen of the United States, residing at Brooklyn, in the county of Kings, and State of New York, have invented a new, original, and ornamental Design for a Pendant, of which the following is a specification, reference being had to the accompanying drawing, forming part thereof.

In the drawing:

Fig. 1 is a front elevational view of a pendant, showing my new design;

Fig. 2 is a side elevational view of the same; and

Fig. 3 is a horizontal sectional view thereof taken on the line 3—3 of Fig. 1.

I claim:

The ornamental design for a pendant, as shown.

MARINDO DE STEFANO.
